[57] CLAIM

The ornamental design for a carrier for compact discs, as shown and described.

DESCRIPTION

FIG. 1 is a perspective view from the front of a carrier for compact discs, showing my new design;

FIG. 2 is a rear elevational view thereof;

FIG. 3 is a bottom plan thereof;

FIG. 4 is a perspective view thereof shown in an open position;

FIG. 5 is an end elevational view thereof; and,

FIG. 6 is a left side elevational view of FIG. 4, top and side flaps being shown repositioned.

Each interior pocketed sheet is understood to have the same front and rear appearances as those sheets shown in FIG. 4.

FIG. 1

FIG. 2

FIG. 3

FIG. 4

FIG. 5

FIG. 6
